UNITED STATES PATENT OFFICE

122,452

DESIGN FOR AN INITIALED NECKTIE FASTENER OR SIMILAR ARTICLE

Charles Silverman, Providence, R. I.

Application November 21, 1939, Serial No. 88,393

Term of patent 3½ years

To all whom it may concern:

Be it known that I, Charles Silverman, a citizen of the United States, residing at 179 Wheeler Avenue, Providence, in the county of Providence and State of Rhode Island, have invented a certain new, original, and ornamental Design for an Initialed Necktie Fastener or Similar Article, of which the following is a specification, reference being had to the accompanying drawing, forming part thereof.

I claim:

The ornamental design for an initialed necktie fastener or similar article, as shown.

CHARLES SILVERMAN.
